(57) **CLAIM**

The ornamental design for an eye drop applicator, as shown and described.

DESCRIPTION

FIG. 1 is a top prospective view of an eye drop applicator showing my new design.

FIG. 2 is a side view thereof.

FIG. 3 is a top view thereof; and,

FIG. 4 is a bottom view thereof.

The broken lines in the drawings depict portions of the eye drop applicator that form no part of the claimed design.
